UNITED STATES PATENT OFFICE.

REINHOLD PROELL, OF DRESDEN, GERMANY.

VARIABLE-PRESSURE REGULATOR.

Application filed March 20, 1925, Serial No. 17,013, and in Germany September 9, 1924.

This invention relates to an indirectly acting pressure regulating-apparatus, in which the motive fluid used to displace a power-piston is regulated by a rotary-valve opening or closing, as may be required, passages arranged in said power-piston. Regulating-apparatus of this kind is well known.

However, so far as I am aware it is new to turn the rotary-valve by a guide-piece or part shaped as a cylinder, drum or pipe, provided with screw-like or helical slot, also causing the automatic return-movement of the rotary-valve by a tappet arranged on said rotary-valve and operating in said slot during the forward and return movement of the power-piston.

Referring to the accompanying drawing forming a part of the specification, in which like numerals designate like parts in the two views,—Fig. 1 is a longitudinal sectional view and Fig. 2 a transversal sectional view of the apparatus—taken on line $x-x$, Fig. 1.

a designates a cylinder and b the power-piston or plunger provided with passages c . Said passages, which can also be arranged in a special part connected with the piston mentioned, are controlled by the rotary-valve d guided within an annular groove provided in the projecting part e of the piston or plunger b . f is a port in said rotary-valve and m is a tappet or arm extending from the rotary-valve. Said rotary-valve is surrounded by a drum or cylinder g in the wall of which is a helical groove or slot h , which acts as a guide for the tappet or arm m .

The cylinder a is provided with an inlet port i at one end thereof and with an outlet port l adjacent the other end thereof. The passages c formed in the piston b and the stem e thereof may be provided as illustrated, or in any other suitable manner, and preferably at the inner end of the stem e the passage c terminates in radially disposed ports c' adapted to be opened and closed by turning the rotary valve d so that the ports f therein register with the ports c' or close the same. Furthermore, the drum g having the helical slot h in which the arm m of the rotary valve operates is normally fixed in position for any given operation of the apparatus, but this drum g may be reversibly adjusted to position, as will be apparent, so as to determine the extent of the movement of the piston which is necessary

to open the rotary valve by causing the ports f thereof to register with the rotary ports c' in the stem e of the piston b .

The mode of operation of the apparatus explained above is as follows:

If the motive fluid supplied by an oil-pump for example enters into the cylinder a at i , it causes a forward stroke of the piston or plunger b , which is prevented from turning in a cylinder by a groove a' and a tongue or pin b' in any other suitable manner. The resistance effected by a distributing-valve motion, shutter or the like is overcome in this manner. This operation is maintained until the rotary-valve is turned by the drum or cylinder to such an extent, that the oil is permitted to flow through the passage c , c' and the ports f . In this operation the piston or plunger b will continue its forward movement until the rotary-valve d is turned by the screw-like slot h to such an extent that the oil may flow or pass through the ports in the valve. In the return movement the piston b moves in the other direction under the influence of a spring k or other equivalent suitable means, until the valve has closed the passages c or reduced the open section of the passages f to such an extent that the pressure of the throttled oil equals the forces acting against the piston b .

The apparatus described allows an extraordinarily intense sensibility to be obtained, for the reason that the rotary-valve may be of light weight and of small length, whereby resistances caused by the viscosity of the oil are prevented. Furthermore, the guiding cylinder g serving for the displacement of the rotary-valve can also be constructed of light weight, as no material pressure is brought to bear against it. After the oil has passed the passages c and f of the piston or plunger b , it issues again from the cylinder a at the port l .

What I claim is:

1. In a variable pressure regulator, a cylinder, a piston movable longitudinally therein, a stem forming part of the piston and having a passage therein, a rotary valve mounted on the stem of the piston, and means for operating the said valve by the movement of the piston.

2. In a variable pressure regulator, a cylinder, a piston movable longitudinally therein, a stem forming part of the piston and having a passage therein, a rotary valve

mounted on the stem of the piston, a drum fixed in the cylinder, and devices cooperating with the drum and the rotary valve whereby in the movement of the piston the 8 rotary valve is opened and closed.

3. In a variable pressure regulator, a cylinder, a piston movable longitudinally therein, a stem extending from the piston and having a passage therein terminating 10 adjacent the end of the stem in radially disposed ports, a rotary valve mounted on the stem and adapted to cover the radial ports in the stem and also to uncover the same by ports provided for this purpose in the valve, 15 a drum having a helical slot therein, and an arm carried by the rotary valve and operating in the helical slot in the drum whereby in the movement of the piston the rotary valve is turned to open and close the same.
- 20 4. In a variable pressure regulator, a

cylinder, a piston movable longitudinally therein, a stem extending from the piston and having a passage therein terminating adjacent the end of the stem in radially disposed ports, a rotary valve mounted on 25 the stem and adapted to cover the radial ports in the stem and also to uncover the same by ports provided for this purpose in the valve, a drum having a helical slot 30 therein, an arm carried by the rotary valve and operating in the helical slot in the drum whereby in the movement of the piston the rotary valve is turned to open and close the same, and a spring for moving the said piston in one direction.

In testimony, that I claim the foregoing as my invention, I have signed my name this 25th day of February, 1925.

REINHOLD PROELL.
